MINER'S FUSE CUTTER

Hallis Baker, Golden, Idaho, assignor to John F. Vanderpool and William H. Baker, Golden, Idaho

Application June 19, 1934, Serial No. 731,356

8 Claims. (CL. 86—22)

The invention relates to a miner's fuse cutter and more especially to a combined fuse cutter and splitter.

The primary object of the invention is the provision of a tool of this character, wherein a plurality of cutting blades are arranged so that a fuse for blasting operation can be cut and split when necessary, the cutting and splitting being carried forth in a single operation and thereby overcoming the necessity for the use of a penknife as is generally employed by shot-firers, and in the use of such knife one operation being required to cut and the other to split the fuse before igniting it, the blades being separable so that the same can be sharpened or repaired, or the placement of new blades as the occasion may require under the use of such tool.

Another object of the invention is the provision of a tool of this character, wherein a miner's fuse can be severed with dispatch and without inconvenience to the user of the tool, this being required particularly when the fuse at the end to be ignited becomes wet or when it is desired to have a determined length of fuse for a blasting operation, the tool being also provided with a wheel or roller cutter for use on a dynamite stick for the splitting of the same prior to the said stick of dynamite being tamped in a drill hole, this cutter minimizing the danger in the handling of the dynamite resultant from friction incident to the use of a fixed blade and also assures safety against cutting the fingers or hands of a shot-firer, the blade being more accurate in service than a penknife or the like.

A further object of the invention is the provision of a tool of this character, wherein the construction thereof is designed solely and particularly for the cutting and splitting of a fuse as employed by shot-firers in mines and eliminating the necessity for the use of a pocket or penknife, which renders this work hazardous and slow.

A still further object of the invention is the provision of a tool of this character which is simple in construction, thoroughly reliable and effective in its purpose, convenient for carriage on the person, readily and easily operated, strong, durable, and inexpensive to manufacture.

With these and other objects in view, the invention consists in the features of construction, combination and arrangement of parts as will be hereinafter more fully described in detail, illustrated in the accompanying drawing, which discloses the preferred embodiment of the in-

vention, and pointed out in the claims hereunto appended.

In the drawing:

Figure 1 is a side elevation of a tool constructed in accordance with the invention. 5

Figure 2 is a top plan view thereof and partly broken away.

Figure 3 is a perspective view of one of the jaws of the tool.

Figure 4 is a fragmentary perspective view of another of the blades of the tool.

Figure 5 is a perspective view of a further jaw of the tool.

Figure 6 is a perspective view of the jaw shown in Figure 5, but the same being inverted. 15

Similar reference characters indicate corresponding parts throughout the several views in the drawing.

Referring to the drawing in detail, the tool embodying the present invention comprises a 20 pair of levers 10 and 11, respectively, these being disposed in crossed relation to each other and pivoted, as at 12, at the crossing point of said levers. The lever 10 is formed with a flat plate-like jaw 13 and the lever 11 has the jaw 14. 25 The jaw 13, at its inner face, has formed therein, transversely of the same, the spaced parallel half-circular grooves 15, one being longitudinally channeled, as at 16, preferably intersecting the innermost groove and providing a seat for 30 a cutting blade 17 aligned with said channel 16 and detachably carried by the jaw 14, the blade being separable from this jaw through the medium of fasteners 18. These grooves 15 in the jaw 13 provide seats for the miner's fuse. 35

Interposed between the jaws 13 and 14 is a third jaw 19, it having the spaced parallel grooves 20 companions to the grooves 15 for accommodating the miner's fuse. The innermost groove 20 has intersecting the same the slot 21 40 for the passage of the blade 17 therethrough and into the channel 16, this blade 17 being for the purpose of longitudinally splitting the fuse for a determined distance of its length.

The third jaw 19 has built thereon a side wall 45 22 which is at right angles thereto and materially strengthens said jaw, the latter being swingingly connected to the pivot 12, it being bifurcated, as at 23, to straddle both levers 10 and 11 at the pivotal point thereof. Interposed between the jaw 14 and the third jaw 19 is a coiled compression spring 24 which serves to urge the jaw 14 away from the jaw 19 to recede the blade 17 away from the grooves 20, while carried by the lever 11 is the leaf spring 25 55

which serves to tension the jaws 13 and 14 and hold the same normally in open or spread apart position, this spring 25 at its free end being in contact with the lever 10, as is clearly shown 5 in Figure 1 of the drawing.

At the outside of the jaw 14 and detachably mounted thereon is a cutting blade 26, this being disposed at right angles to the blade 17, and such blade 26 plays through a clearance 27 in 10 the third jaw 19 and operates in the slot 28 in the jaw 13, the purpose of the blade 26 being adapted to sever or cut the fuse in desired lengths simultaneously with the longitudinal splitting of said fuse, both blades 17 and 26 15 being formed with the straight beveled cutting edges 29.

On the jaw 14 opposite to the blade 26 is a 20 relatively narrow blade 30, this being detachably carried by said jaw 14 and offset laterally with respect thereto, while upon the jaw 14 and separable therefrom is the blade 31 companion to the blade 30, these blades being adapted for the cutting of fuse when presented to the blades outside of the grooves 15 and 20 which are 25 companions to each other.

The third jaw 19 carries a stop 32 engaging an abutment lug 33 on the lever 10, so as to limit the swinging movement of the jaw 19 in one direction.

30 It should be apparent that when the fuse is placed within the outermost groove 15 in the jaw 13 the said fuse will be severed but not longitudinally split. On the placing of the fuse in the innermost groove 15 in the jaw 13 the 35 said fuse will be severed and longitudinally split.

The lever 10 close to the pivot 12 carries a swinging latch 34 to engage a keeper 35 on the lever 11 and this latch holds the tool closed, or the jaws 13, 14 and 19 together.

40 On the lever 10, at the handle end thereof, is a bearing 36 in which is pivoted, at 37, a swinging carrier 38 for a rotatable disk-like cutting wheel 39 and said carrier 38 when swung outwardly brings the cutting wheel 39 into a position 45 for use for the splitting of dynamite sticks, the carrier 38 being swung inwardly to have the cutting wheel 39 protected by a guard projection 40 when the said wheel 39 is inactive for use. The carrier 38 in its mounting is designed to act in conformity with the blades of a pen or 50 pocket knife, as said carrier is frictionally held in either thrown position.

The jaw 13 carries guiding pins 41 coacting with guide openings 42 in the jaw 19 and through the instrumentality of these, the jaws 13 and 55 19 are held in aligned relation to each other, particularly when the said jaws are brought together under a straining action.

The channel 16 in the jaw 13 has a filling 43 60 of an alloy, as for example, copper, brass, bronze, lead or any other soft metal or material to avoid dulling of the cutting edge of the blade 17 when the tool is in use.

On the lever 11, at the handle end thereof, is 65 permanently placed a thimble 44, or the latter is formed from this end, and the purpose of said thimble is to enable the tool to be used for making a hole in a stick of dynamite.

What is claimed is:

70 1. A tool of the character described comprising a pair of pivotally connected levers disposed in crossed relation to each other, jaws formed on the respective levers, another jaw arranged between the jaws on said levers and supported by 75 the pivot connecting said levers, one of the jaws

on the levers and the said other jaw having companion spaced parallel grooves transversely thereof, and cutting blades on one lever jaw and operating crosswise of the grooves and longitudinally of a pair of opposed grooves and centrally of the same.

2. A tool of the character described comprising a pair of pivotally connected levers disposed in crossed relation to each other, jaws formed on the respective levers, another jaw arranged 10 between the jaws on said levers and supported by the pivot connecting said levers, one of the jaws on the levers and the said other jaw having companion spaced parallel grooves transversely thereof, cutting blades on one lever jaw 15 and operating crosswise of the grooves and longitudinally of a pair of opposed grooves and centrally of the same, and a compression spring acting against the said other jaw and the lever jaw next thereto.

3. A tool of the character described comprising a pair of pivotally connected levers disposed in crossed relation to each other, jaws formed on the respective levers, another jaw arranged 20 between the jaws on said levers and supported by the pivot connecting said levers, one of the jaws on the levers and the said other jaw having companion spaced parallel grooves transversely thereof, cutting blades on one lever jaw and operating crosswise of the grooves and longitudinally of a pair of opposed grooves and centrally of the same, a compression spring acting against the said other jaw and the lever jaw next thereto, and a stop for said other jaw to limit the 25 swinging movement thereof in one direction.

4. A tool of the character described comprising a pair of pivotally connected levers disposed in crossed relation to each other, jaws formed on the respective levers, another jaw arranged 30 between the jaws on said levers and supported by the pivot connecting said levers, one of the jaws on the levers and the said other jaw having companion spaced parallel grooves transversely thereof, cutting blades on one lever jaw and operating crosswise of the grooves and longitudinally of a pair of opposed grooves and centrally of the same, a compression spring acting against the said other jaw and the lever jaw next thereto, and a stop for said other jaw to limit the 35 swinging movement thereof in one direction.

40 5. A tool of the character described comprising a pair of pivotally connected levers disposed in crossed relation to each other, jaws formed on the respective levers, another jaw arranged 45 between the jaws on said levers and supported by the pivot connecting said levers, one of the jaws on the levers and the said other jaw having companion spaced parallel grooves transversely thereof, cutting blades on one lever jaw and operating crosswise of the grooves and longitudinally of a pair of opposed grooves and centrally of the same, a compression spring acting against the said other jaw and the lever jaw next thereto, a stop for said other jaw to limit the 50 swinging movement thereof in one direction, and a latch carried by one lever and engageable with the other to hold the jaws together.

55 6. A tool of the character described comprising a pair of pivotally connected levers disposed in crossed relation to each other, jaws formed on the respective levers, another jaw arranged 60 between the jaws on said levers and supported by the pivot connecting said levers, one of the jaws on the levers and the said other jaw having companion spaced parallel grooves transversely thereof, cutting blades on one lever jaw and operating crosswise of the grooves and longitudinally of a pair of opposed grooves and centrally of the same, a compression spring acting against the said other jaw and the lever jaw 65 next thereto, a stop for said other jaw to limit the swinging movement thereof in one direction, a latch carried by one lever and engageable with the other to hold the jaws together, and a spring spreading the levers apart from each other.

70 7. A tool of the character described comprising a pair of pivotally connected levers disposed in crossed relation to each other, jaws formed on the respective levers, another jaw arranged between the jaws on said levers and supported by 75

- the pivot connecting said levers, one of the jaws on the levers and the said other jaw having companion spaced parallel grooves transversely thereof, cutting blades on one lever jaw and operating crosswise of the grooves and longitudinally of a pair of opposed grooves and centrally of the same, a compression spring acting against the said other jaw and the lever jaw next thereto, a stop for said other jaw to limit the swinging movement thereof in one direction, a latch carried by one lever and engageable with the other to hold the jaws together, a spring spreading the levers apart from each other, and a cutting wheel swingingly supported on one of said levers. 5
7. A tool of the character described comprising a pair of pivotally connected levers disposed in crossed relation to each other, jaws formed on the respective levers, another jaw arranged between the jaws on said levers and supported by the pivot connecting said levers, one of the jaws on the levers and the said other jaw having companion spaced parallel grooves transversely thereof, cutting blades on one lever jaw and operating crosswise of the grooves and longitudinally of a pair of opposed grooves and centrally of the same, and a filling of soft material located at one of the transverse grooves and operative to prevent dulling of the blade confronted thereby. 10
8. A tool of the character described comprising a pair of pivotally connected levers disposed in crossed relation to each other, jaws formed on the respective levers, another jaw arranged between the jaws on said levers and supported by the pivot connecting said levers, one of the jaws on the levers and the said other jaw having companion spaced parallel grooves transversely thereof, cutting blades on one lever jaw and operating crosswise of the grooves and longitudinally of a pair of opposed grooves and centrally of the same, a compression spring acting against the said other jaw and the lever jaw next thereto, a stop for said other jaw to limit the swinging movement thereof in one direction, a latch carried by one lever and engageable with the other to hold the jaws together, a spring spreading the levers apart from each other, and a keeper for said cutting wheel. 15
